Inventor:
LEE E. BERRY
Donee Rain Kinsee
attk.

UNITED STATES PATENT OFFICE.

LEE E. BERRY, OF CHICAGO, ILLINOIS.

GARTER.

Application filed November 15, 1923. Serial No. 674,974.

The invention relates to garters and an improved clasp for making them.

One of the objects of the invention is to provide a clasp by the use of which a complete garter for hose may be made from a single continuous strip of webbing.

Another object is to provide a clasp by which the effective length of the webbing may be adjusted and positively held in adjusted position.

Another object is to generally improve clasps, and garters that may be made by its use.

Other objects and advantages will readily appear from a consideration of the following description, when taken in conjunction with the drawings, forming a part hereof, wherein:

Fig. 1 shows one form of garter that may be made by use of my improved clasp.

Fig. 2 is an enlarged end elevation of one member of the clasp.

Fig. 3 is a side elevation thereof.

In all the views the same reference characters are employed to indicate similar parts.

The clasp consists of two members, the major, novel member 5 and the cooperating minor or hook member 6.

The major member is made in one single piece and consists, as shown, of the bar 7 having inwardly projecting spears 8. Each of these spears has a sharply pointed head 9 and a constricted neck 10. A parallel bar 11 is spaced from the rear bar 7 to leave an opening 12 within which the spears are contained. The bars 7 and 11 are joined by cross members 13. At the juncture of the bar 11 and the cross members 13 is an enlargement 14 perforated at 15 by which the member 5 may be attached to the protecting pad 16, as shown at 17.

The bar 11 is also enlarged at its longitudinal median portion, as at 18, which portion is perforated, as at 19, to receive the hook 20 of the member 6. A bead 21' is formed around the aperture 19 to give greater strength to the bordering material 18.

The parts 18 and 21' occupy a plane laterally displaced from the plane occupied by the bar 7 and the enlargements 14, leaving the latter flat for better attachment to the pad 16 and raising the part 18 to better accommodate the hook 20.

There is sufficient space between the heads 55 of the spears and the bar 11 thru which to pass the fabric.

The clasp member 5 is secured to the protecting pad 16, as by eyelets, or otherwise, as at 17, thru the openings 15 of the enlarged 60 corners 14.

In making the garter, the webbing is passed inwardly through opening 12 and the end 23 is deflected downwardly at an angle 65 from the band 22 and the spears 8 are caused to pierce the webbing. By attaching the clamp member 5 to the pad 16 in such manner that the longitudinal aperture 12 therein is so disposed that the spears 8 engage the webbing on a line forming an angle 70 oblique to the longitudinal edges of said webbing, said line forming the division between the band and tab, a construction is afforded whereby but a single aperture is 75 required in the clasp member, and the webbing folds without crease to form the depending tab 23. To adjust the size of the band 22 thus formed, the slide 6' is moved along the webbing as usual.

The spears, having enlarged pointed heads 80 and constricted necks, will retain the webbing in place without liability to displacement. The webbing being elastic will be distended to pass over the heads and will then contract around the necks. For this 85 reason the fabric is not materially injured.

On account of the elasticity of the webbing it is difficult to hold it in an ordinary buckle because it will contract its transverse 90 dimensions when strain is applied to it and slip through the buckle, and the tines of the ordinary buckle, when a buckle of this type is used, are thin and sharp and are apt to tear the webbing.

The member 5 holds the webbing without 95 the employment of another relatively movable part, as in the usual buckle.

When the webbing is adjusted on the spears, such adjustment is liable to endure 100 for some time and seldom, if ever, are the spears removed from the perforations they make and reinserted in the same perforations; therefore there is very little wear of the fabric.

The metal structure disclosed herein may 105 be used many times with new webbing and thus substantially new garters may be had for a trifling cost. The act of attaching the

webbing to the holding devices is so easily accomplished it may be done by the purchaser when new webbing is required.

Having described my invention what I claim as new and desire to secure by Letters Patent, is:—

A garter, comprising a band and a tab formed of one piece of elastic webbing, a pad, a clasp member attached to said pad and formed with a longitudinal aperture, web perforating spears formed on one side

of said aperture and engaging said webbing on a line forming an angle oblique to the longitudinal edge of the latter, said line forming the division between the band and tab, and a member on the other end of said band adapted detachably to engage said clasp member.

In testimony whereof I hereunto set my hand.

LEE E. BERRY
